(57) **CLAIM**

We claim the ornamental design for a portable table, as shown and described.

DESCRIPTION

FIG. 1 is a perspective view of a portable table, showing the closed top separately for clarity of disclosure;

FIG. 2 is a top plan view thereof;

FIG. 3 is a perspective view showing the top lid portion of the table separately for clarity of disclosure;

FIG. 4 is a bottom perspective view showing the table top separately for clarity of disclosure;

FIG. 5 is a top perspective view of the table with the top lid removed and the legs removed and in stowed position shown separately for clarity of disclosure;

FIG. 6 is a top perspective view showing the top open with the lid removed shown separately for clarity of disclosure;

FIG. 7 is a perspective view of the leg shown in exploded condition and separately for clarity of disclosure;

FIG. 8 is a perspective view of the leg shown separately for clarity of disclosure;

FIG. 9 is a bottom perspective view of the table in exploded condition;

FIG. 10 is a top perspective view of the table; and,

FIG. 11 is a bottom perspective view of the table.

The hand shown in FIG. 9 is for environmental purposes only and forms no part of the claimed design.
